NO. 14,094

July 17, 1883

UNITED STATES PATENT OFFICE.

HANS T. JOHNSON, OF CHICAGO, ILLINOIS.

DESIGN FOR A WALL-POCKET.

SPECIFICATION forming part of Design No. 14,094, dated July 17, 1883.

Application filed May 14, 1883. Term of patent 3½ years.

To all whom it may concern:

Be it known that I, HANS T. JOHNSON, of Chicago, county of Cook, State of Illinois, and United States of America, have invented a new and original Design for Wall-Pockets, of which the following is a specification, reference being had to the accompanying photographic illustration, forming a part thereof, in which the figure is a perspective representation of my newly-designed wall-pocket.

Heretofore wall-pockets have been made with solid backs and fronts, and with slats, cross-bars, and paneled with wood, straw-board, and ornamented in various ways, and the backs of the pockets made by legs or struts to be supported from the floor.

My new design differs from those heretofore made in that I employ a back and front frame of the same pattern, only the back frame is higher than the front one, and sometimes carved or ornamented at its edges.

In the drawing, A represents the back frame, and B the front frame. R represents the flat panel to the back frame, and D E the ribbed panel to the front frame. The different curves of the front frame are represented by the letters d c b a, which indicate curved lines of the same form as the lines indicated by the same letters on the back frame. f e represent straight lines on both frames. These two frames thus formed, with the addition of desirable carving, F m m, to the back frame, as shown, give a more elegant and costly appearance, and constitute the design.

I claim—

The design for wall-pockets herein shown, consisting of the frames A B, formed with the same straight lines and curves and of the same kind of molding, the back frame being higher than the front one, and ornamented with carving at its edges.

HANS T. JOHNSON.
